UNITED STATES PATENT OFFICE.

WILLEM APPEL, OF SOERABAYA, DUTCH EAST INDIES.

CENTRIFUGAL SEPARATING MACHINE.

Application filed March 14, 1925. Serial No. 15,619.

To all whom it may concern:

Be it known that I, WILLEM APPEL, a citizen of the Dutch East Indies, a resident of the city of Soerabaya, Dutch East Indies, have invented certain new and useful Improvements in Centrifugal Separating Machines, of which the following is a full, clear, and exact specification.

My invention relates to improvements in centrifugal separating machines and especially in those used for the separation of the syrup from crystalline sugar and having a perforated outer wall, a perforated inner plate, or the like, and an intermediate perforated corrugated plate.

The object of the invention is to provide a centrifugal separating machine which exercises less resistance against the flow of the syrup towards the outlet openings after the same has passed the perforated inner plate than is the case in machines now generally in use. Another object is to provide a method of reducing this resistance. Still another object is to provide a corrugated or waved plate suited to be used in centrifugal separating machines for the purpose of diminishing the resistance to the flow of the syrup.

The wall of an ordinary centrifugal machine comprises an intermediate member made of gauze and situated between a perforated inner plate and a perforated outer wall, or drum. I will presume that the machine is used for separating syrup from crystalline sugar.

During the operation of the machine the syrup flows first between the crystals and then passes through the perforations of the inner plate and is evenly distributed over the gauze and passes therethrough.

The gauze usually employed has about 480 meshes per 10 square inches and as in a rather short time a sticky waxy mass is deposited between the wires of the gauze and the wall of the machine, there are formed 480 cells with nearly closed side walls.

In the outer wall of the machine there are only about 6 openings per 10 square inches and the syrup, which lies divided in 480 cells per 10 square inches will only reach the said 6 openings with great difficulty. Such a wall, provided with one intermediate wire gauze, exercises such a great resistance against the flow of the syrup towards the outlet openings, that it has been proposed

in various ways to reduce this resistance, without lengthening the time necessary for treatment, but always without success up to the present.

According to my present invention an intermediate plate is used between the inner plate and the outer wall which plate is corrugated, or waved, the corrugations, or waves, running vertically and having sloping sides and being perforated, or provided with openings, all situated in the same sloping side of the respective corrugations, or waves, or of alternate corrugations, or waves, or any desired number of them, so that the perforations, or openings, when the apparatus is in use are at, or about, right angles to the direction of flow of the syrup. To obtain a still better effect the said perforations, or openings, may also extend somewhat over either, or both, of the bends of the waves, or corrugations.

One of the slopes of each corrugation, or wave, may be steeper than the other and the perforations, or openings, be in the steeper of them.

In this manner the flowing away of the syrup is facilitated because, after it has passed the perforations of the inner plate it can readily pass to the perforations in the outer wall, or drum, the resistance being so much lessened that the time for the separating operation is considerably diminished, say by about twenty per cent.

In the accompanying drawing,

Figure 1 shows in horizontal section part of a wall of a centrifugal machine provided with means in accordance with this invention, this also being drawn to an enlarged scale.

Figure 2 is a front view of part of a corrugated or waved plate in accordance with the invention.

The perforated inner plate is marked 1 and the perforated outer wall, or drum, is marked 2.

The direction of rotation of the machine is indicated by the arrow 4 and the movement of the syrup relative to the wall is indicated by the arrows 5.

Between the plate 1 and the wall 2 a perforated, corrugated or waved, plate 6 is arranged; and the slopes of the corrugations, or waves, wherein perforations 6' are made, are situated at about right angles to the direction of movement of the syrup as indicated by the arrows 5, the direction of

the rotation of the machine being indicated by the arrow 4.

The diminishing of the resistance obtained with this improved construction is due to the fact that the corrugations, or waves, form between the plate 6 and the drum 2 a number of tunnels 7, which throughout their length connect the perforations with each other and form free passages for the syrup. For example, in a centrifugal machine of thirty inches diameter the circumference of which is about ninety five inches, when corrugations of about 0.24 of an inch are used, there will be 10 say 400 corrugations, or waves, over the whole circumference. If the height of the wall be 18 inches, the surface of the wall will be about 1710 square inches. Assuming that, in the outer drum, there are six 15 perforations per ten square inches then the total number of perforations in the drum will be about 1026. The tunnels 7 are roomy enough to allow the separated syrup to pass, without much resistance, to the perforations 20 of the drums and by placing the perforations at about right angles to the direction of flow of the syrup there is very little hindrance to the flow of the syrup into the said tunnels.

30 This reduction of resistance is very great as compared with a wall provided with gauze, especially where particles may be present in the matter driven off.

In the form of the invention illustrated 35 the unperforated sides of the corrugations, or waves, serve as guides to each perforation.

The improved action is increased when the perforations not only occupy the slopes of the corrugations, or waves, but also extend somewhat over the bends thereof as this still more diminishes the resistance, increases the free circulation and avoids the deposit of syrup in so-called "dead places".

40 In applying the corrugated, or waved, plate to the machine care must be taken that it is placed in the right position as to the direction of rotation and consequent flow of the syrup. If the plate were placed upside down in the machine the perforated slopes would be parallel to the direction of the movement of the syrup and the unperforated slopes at right angles thereto, which would of course be very unfavourable to the action.

45 Although I have referred to the machines as being used for separating syrup from

crystalline sugar, the said machines can of course be also used for any other separating purpose for which they may be suitable.

I claim:

1. In a centrifugal separating machine, a 60 perforated outer wall, a perforated inner plate, a member interposed between the wall and plate, said member comprising a perforated corrugated plate with its corrugations extending parallel to the axis of the machine, all its perforations being in corresponding sloping sides of the corrugations. 65

2. In a centrifugal separating machine, a 70 member comprising a perforated corrugated plate with its corrugations extending parallel to the axis of the machine, all its perforations being in corresponding sloping sides of the corrugations.

3. In a centrifugal separating machine, a 75 perforated outer wall, a perforated inner plate, a member interposed between the wall and plate, said member comprising a perforated corrugated plate with its corrugations extending parallel to the axis of the 80 machine, all its perforations being in corresponding sloping sides of the corrugations, said perforations extending somewhat over at least one of the adjacent bends limiting each said corresponding sloping side. 85

4. A perforated corrugated plate for centrifugal machines, all the perforations being situated in corresponding sloping sides of the corrugations, one sloping side of each corrugation being steeper than the other, the 90 perforations being in the steeper sides.

5. A perforated corrugated plate for centrifugal machines, all the perforations being situated in corresponding sloping sides of the corrugations, the perforations extending 95 somewhat over at least one of the bends defining each of said sloping sides, one sloping side of each corrugation being steeper than the other, the perforations being in the steeper sides. 100

6. In a centrifugal separating machine, a member comprising a perforated corrugated plate with its corrugations extending parallel to the axis of the machine, all its perforations being in corresponding sloping sides of the corrugations, one sloping side of each corrugation being steeper than the other and the perforations being in the steeper sides. 105

In testimony whereof, I have signed my 110 name to this specification.

WILLEM APPEL.
